UNITED STATES PATENT OFFICE.

HORATIO F. HICKS, OF ASHLAND, OREGON.

ORE-CONCENTRATOR.

SPECIFICATION forming part of Letters Patent No. 477,934, dated June 28, 1892.

Application filed October 7, 1891. Serial No. 408,058. (No model.)

To all whom it may concern.

Be it known that I, HORATIO F. HICKS, of 5
Ashland, in the county of Jackson and State
of Oregon, have invented a new and Improved
Ore-Concentrator, of which the following is a
full, clear, and exact description.

My invention relates to improvements in
ore-concentrators; and the object of my in- 10
vention is to produce a simple and economi-
cal concentrator which will rapidly separate
the precious particles of the metal from the
light and worthless portion of the pulp, and
which is especially adapted for separating the
refractory metallic particles and sulphurets
15 from the tailings of gold or silver extracting
mills.

To this end my invention consists in cer- 20
tain features of construction and combina-
tions of parts, which will be hereinafter de-
scribed and claimed.

Reference is to be had to the accompanying
drawings, forming a part of this specification,
in which similar figures of reference indicate
corresponding parts in both the views.

25 Figure 1 is a vertical cross-section of the
concentrator, and Fig. 2 is a vertical longi-
tudinal section of the same.

The concentrator is provided with a main
30 open-ended drum or cylinder 10, which is
provided with the usual body-cog 10^a to fa-
cilitate its rotation, and the cylinder is held
to turn on the ordinary supporting-rollers 11.
Within the cylinder and at the ends of the
35 same are annular flanges 12, which project
inward from the walls of the cylinder and
which are of dissimilar height, the middle
flanges being the highest and the height of
the flanges gradually diminishing toward
40 each end. The cylinder is fed by a flume 13,
which delivers into the center of the cylinder
and the delivery of which is preferably
through the perforated sides 14. Near one
45 side of the cylinder and adjacent to that side
which turns upward is a pipe 15, which is
adapted to supply clean water to the cylinder
and which has on the side nearest the cylin-
der-wall jet-openings 16, so that jets of water
will issue from the pipe against the wall, thus
keeping the wall washed clean and supply-

ing sufficient water to make the concentrator 50
work efficiently.

The operation of the concentrator is as fol-
lows: The pulp which flows through the flume
will be discharged through the side or jet
openings 14 against the walls of the cylinder 55
and above the water-line and the sulphurets
will drop downward between the flanges of
the cylinder. It will be seen that the water
supplied to the cylinder will rise above the
flanges so that it will flow outward at each 60
end, and as the cylinder is constantly rotated
there will also be a cross-current of water, and
the two currents, together with the movement
of the cylinder, will cause the pulp to be thor-
oughly agitated, so that the light and worth- 65
less matter will flow off while the concen-
trates will remain between the flanges, and
the progressive decrease in the height of the
flanges as they approach the ends of the cyl-
inder will cause the tailings to be thoroughly 70
worked over and all the concentrates will be
retained in the cylinder.

Having thus fully described my invention,
I claim as new and desire to secure by Letters
Patent—

75 1. An ore-concentrator comprising a revolu-
ble open-ended cylinder having internal
flanges and a feed-flume arranged to deliver
centrally in the cylinder, said flume having a
series of side openings at its delivery end, 80
substantially as described.

2. In an ore-concentrator, the open-ended
cylinder having a series of flanges therein,
the flanges being highest in the middle and
gradually diminishing in height toward the 85
ends of the cylinder, substantially as de-
scribed.

3. An ore-concentrator comprising an open-
ended cylinder having a series of internal
flanges, which flanges are highest in the mid- 90
dle of the cylinder and diminish in height to-
ward the end, and a feed-flume arranged to de-
liver centrally within the cylinder, substan-
tially as described.

HORATIO F. HICKS.
